COMBINED FOOD SHAKER AND BLENDER

James B. Swett, Barrington, R.I., and Sidney Z. Smith,
Worcester, Mass., assignors to Dart Industries Inc.,
Los Angeles, Calif.

Filed Apr. 13, 1973, Ser. No. 350,873

Term of patent 14 years

Int. Cl. D7—01

U.S. Cl. D7—51

FIG. 1

FIG. 2

FIG. 3

FIG. 1 is a side elevational view of a combined food shaker and blender showing our new design;

FIG. 2 is a top plan view thereof; and

FIG. 3 is a bottom plan view.

We claim:

The ornamental design for a combined food shaker and blender, substantially as shown.
